(57) **CLAIM**

The ornamental design for a front portion of a motor vehicle, as shown and described.

DESCRIPTION

FIG. 1 is a front perspective view of a front portion for a motor vehicle showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top plan view thereof.

The bottom view of the front portion of the motor vehicle forms no part of the claimed design. The de-emphasized and halftone portions shown in the photographs illustrate environmental structure for the front portion of the motor vehicle that forms no part of the claimed design.

1 Claim, 5 Drawing Sheets
